CAN

Harry Sebell, Newton Highlands, Mass., assignor
to Bell Products Corporation, Boston, Mass., a
corporation of Massachusetts

Application January 22, 1947, Serial No. 723,637

1 Claim. (Cl. 220—54)

1

This invention relates to cans of the type which are opened by tearing out a tear-strip from the can body and in which the can body has an interior collar element with which the end closure or cover element has a tight friction fit.

One object of the invention is to provide a can of this type with a novel collar element which provides ample space between it and the cover element to receive the end of a screw driver or other implement used to pry the cover from the can body after the tear-strip has been removed.

A further object of the invention is to provide a can with an improved collar element which is so constructed that the surfaces which provide the tight friction fit between the collar and cover element will not be deformed or marred by the operation of prying the cover from the collar, so that when the cover is replaced on the can body, it will have the same tight friction fit that it had before the can was opened.

In order to give an understanding of the invention, I have illustrated in the drawings a selected embodiment thereof which will now be described and after which the novel features will be pointed out in the appended claim.

In the drawings:

Fig. 1 is a partial sectional view of a can embodying my invention.

Fig. 2 is a fragmentary side elevation thereof.

Fig. 3 is an enlarged fragmentary sectional view through one side of the can.

Fig. 4 is a sectional view illustrating the can after it has been opened.

In the drawings 1 indicates the can body, 2 the end closure or cover element, and 3 the collar element.

Said collar element is made from sheet metal, and it presents the outer cylindrical wall 4 which engages the inside of the can body, and the inner vertical cylindrical wall 6 which defines the opening 7 in the can after the latter has been opened and the top wall 5 connecting the inner and outer cylindrical walls. The lower edge of the inner cylindrical wall 6 is rolled into a bead 8 thus providing said wall with a wire edge. The top wall 5 of the collar has a stepped formation, it presenting an inner, annular, horizontally extending, flat portion 21 and an outer, annular, horizontally extending, flat portion 18 that surrounds said inner flat portion and is offset downwardly relative thereto, said inner and outer flat portions occupying parallel but spaced apart planes and the outer edge of the inner flat portion being connected to the inner edge of the outer

2

flat portion by an annular vertical wall portion 22.

The end closure 2 is of the usual construction which is formed from a sheet metal blank that is deformed to present the vertical cylindrical wall 9 which fits within the inner wall 6 of the collar with a tight friction fit, and also to present the flat horizontally extending portion 10 outside of the wall 9 which overlies and rests on the inner, annular, flat portion 21 of the collar and which also extends over but in spaced relation to the outer annular flat portion 18 of said collar, the marginal portion of the end closure being bent upwardly against the inside of the can body 1 as shown at 11 and being permanently secured and hermetically sealed to the upper edge of the can body in some suitable way, as by means of the lock seam 12. The inner, annular, flat portion 21 of the top wall 5 of the collar thus constitutes a seat for the cover element.

The can body 1 is provided with two circumferential score lines 13, 14 that form between them a tear-strip 15 that can be torn out to open the can.

25 The score line 13 is situated above the inner, annular, flat portion 21 of the collar element and the score line 14 is situated below the outer, annular, flat portion 18 of said collar element. When the can is initially sealed as shown in Figs. 1 and 3, there will exist an annular circumferential space 19 between the outer marginal part of the horizontal flat portion 10 of the cover element and the outer, annular, flat portion 18 of the collar element, which space has parallel upper 30 and lower walls, the vertical wall portion 22 constituting the inner wall of said space and the outer wall being constituted by the tear-strip portion 15 of the can body.

Hence when the can is to be opened by tearing out the tear-strip 15, the circumferential space or groove 19 having flat top and bottom walls will be open or exposed on its outer face for the reception of a screw driver or other implement used to pry the cover 2 free from the wall 6 of the collar. This can be accomplished by inserting the end of a screw driver or other similar implement into the space 19 and turning it about its longitudinal axis so that one side edge of the screw driver exerts a lifting force on the outer 45 marginal portion of the horizontal portion 10 of the cover element, and the other side edge of said screw driver exerts a downward force on the off-set portion 18 of the collar. Or the loosening of the cover may be accomplished by inserting one end of a suitable implement into the space 19

and exerting a downward force on the other end of said implement, using as a fulcrum for the instrument the corner where the offset portion 18 merges with the wall 4 of the collar.

In either case the operation of removing the cover is much facilitated by the flat horizontal top and bottom walls of the space 19, because the parallel arrangement of these walls has no tendency to force the implement out of the space during the cover removing operation.

The space 19 of an unopened can is thus concealed and protected by the tear-strip so that nothing can become lodged in said space during transportation, storage, or any other manipulation of the can before it is opened.

The score lines are preferably so located that before the tear-strip is torn out, its upper edge rests against and is backed by the lower portion of the vertical wall 11 of the cover element, and its lower edge rests against and is backed by the upper portion of the outer vertical wall 4 of the collar 3. An advantage of this arrangement is that it eliminates any danger that the wall of the can body will become broken through at any point along a score line by a blow accidentally struck against the tear-strip.

Another advantage of this construction is that the cover element 2 may be pried free from the collar without danger of marring or deforming either the wall 6 of the collar or the wall 9 of the closure which form between them a tight friction fit. Furthermore, any prying action which takes place in freeing the closure from the collar is resisted largely by the vertical wall 4 of the collar and the vertical portion 11 of the closure, and hence the removal of the cover can be accomplished without deforming or injuring the surfaces of the collar and cover which form between them a tight friction fit. After the can has been initially opened by removing the tear strip 15 and prying the cover element free from the collar, said can can be resealed again by replacing the cover in the collar, and since the operation of prying the cover free from the collar can be performed without distorting or deforming either the vertical wall 6 of the collar or the wall 7 of the cover, the same tight friction fit between the cover and the collar will exist after the can has been reclosed as existed when the can was first sealed.

When the cover has been thus replaced on the can, it occupies the same position as it had when the can was first sealed, that is, with the horizontal wall 10 of the cover resting against and seated on the flat top wall 5 of the collar. As a result the space 19 on the resealed can will be open and exposed for the reception of a screw driver or other implement used for again prying the cover loose when it is desired to reopen the can.

The score lines 13, and 14 may extend clear around the can body or they may be so formed as to extend nearly but not entirely around said

can body. In the latter case, there will exist an unscored portion 20 between the ends of the score lines which will form a hinged portion for the closure after the tear-strip has been removed as indicated in Fig. 4.

I claim:

A can having a can body, a cover-receiving collar element located within the can body and presenting an outside cylindrical wall engaging the wall of the can body, a vertical inner cylindrical wall which defines the cover-receiving opening of the can and a top wall connecting said inner and outer cylindrical walls, said top wall having a stepped formation and presenting an inner, annular, horizontal, flat portion and an outer, annular, horizontal, flat portion which is offset downwardly relative to said inner flat portion and which is parallel thereto, the outer edge of the inner annular flat portion being connected to the inner edge of the downwardly offset outer annular flat portion by a vertical wall portion, a cover element having a vertical cylindrical wall which fits the inner cylindrical wall of the collar with a tight friction fit, the portion of the cover element outside of its said vertical cylindrical wall occupying a horizontal plane and extending over and in contact with the inner, annular, flat portion of the top wall of the collar and over but spaced from the outer, annular, horizontal, flat portion of said top wall, the peripheral edge portion of said cover element being permanently connected and hermetically sealed to the top edge of the can body, said can body having two circumferential score lines forming between them a tear-strip which can be torn out to open the can, one score line being situated above the inner, annular, flat portion of the top wall of the collar and the other score line being situated below the outer, annular, flat portion of said collar, said outer, annular, flat portion of the collar element and the peripheral marginal portion of the horizontally extending portion of the cover forming between them a circumferential groove having flat parallel top and bottom walls which, before the can is opened, is closed by the tear-strip portion of the can body, but when the tear-strip is removed is exposed for the insertion of an implement to pry the cover free from the collar element.
